UNITED STATES PATENT OFFICE.

JOHN S. WINCRANTZ, OF PITTSBURGH, PENNSYLVANIA, ASSIGNOR TO SAMUEL S. NEWMAN, OF PITTSBURGH, PENNSYLVANIA.

GRINDING-MACHINE ATTACHMENT.

1,113,394.

Specification of Letters Patent. Patented Oct. 13, 1914.

Application filed May 13, 1914. Serial No. 838,200.

To all whom it may concern:

Be it known that I, JOHN S. WINCRANTZ, a citizen of the United States, residing at Pittsburgh, in the county of Allegheny and State of Pennsylvania, have invented certain new and useful Improvements in Grinding-Machine Attachments, of which the following is a specification.

The invention relates to attachments for use in connection with grinding machines, such attachments being primarily intended for use in grinding adzes and scythes. The invention has for its principal objects; the provision of an attachment which will securely hold adzes of various sizes and contours; the provision of an attachment in which all lost motion in the sliding wear parts is automatically taken up; the provision of an attachment wherein improved means are provided for adjusting the tool clamping bar; and the provision of improved means upon the attachment and grinding machine whereby scythes (regardless of size and shape) are properly guided and supported with respect to the grinding surface. One embodiment of the invention is illustrated in the accompanying drawings wherein;

Figure 1 is a front elevation of the machine with a scythe and adz supported by the attachment and in section, and Fig. 2 is a side elevation of the same attachment with the adz and scythe blades shown in dot and dash lines.

In the construction as illustrated in Figs. 1 and 2, 1 is a grinding disk which is rotated from the handle 2, a train of gearing being interposed between, and lying in the casing 3; 4 is a conical grinding wheel which is mounted removably upon the axle of the disk wheel in any desired manner; and 5 is a U-shaped bracket having a shank 6 secured detachably in position upon the machine by means of the set screw 7, the method of mounting the bracket being one well known in the art.

Secured between the two upright arms 8 and 9 (Fig. 1) of the bracket 5 is a guide rod 10, and mounted upon this rod 10, for sliding and rocking movement, is the tool carrying frame 11. This frame 11 is adapted to carry the adz 12 to be ground, the blade of such adz being securely clamped between the fixed bottom bar 13 and the

movable clamping bar 14. As indicated in Fig. 1, the upper surface of the bar 13 is preferably made concave so that the blade 12 does not engage such bar at its central portion, but only adjacent its edges. The purpose of this feature of construction is to provide a firm two-point support for the lower side of the blade regardless of its contour, so that all blades, ranging from those much flatter upon the lower surface than the one illustrated to those much more curved, will all be engaged by the bar 13 at widely separated points, thus eliminating any tendency of the blade to rock upon the bar 13 such as would occur if the rounded lower face of the blade touched only at its central portion.

The ends of the clamping bar 14 are guided upon the portions 15-16 of the frame 11, such guiding being accomplished by making the ends forked as indicated at 17 in Figs. 1 and 2, so that such ends partially surround the upright bars 15 and 16. As indicated in dotted lines in Figs. 1 and 2, the clamping bar 14 is made U-shaped in cross section, thus making the bar lighter and providing a space for the cotter pin 18 (Fig. 1) by means of which the central adjusting screw 19 is swiveled. The central screw 19 is threaded through the top bar 20 of the frame 11, and its reduced end extends through the top wall of the clamping bar 14, the cotter 18 extending through a perforation in the lower end of the screw. By this means the screw is swiveled to the bar 14 so that the bar may be moved both downward and upward by the operation of the center screw. On either side of the screw 19 are the screws 21 which are also threaded through the bar 20 and which bear at their lower ends upon the top surface of the bar 14. The advantage incident to the use of the central swivel screw in connection with the two side screws which are not swiveled will be readily apparent. If all three screws were swiveled, the moving of the bar 14 back and forth would be a tedious operation, since the screws would necessarily have to be adjusted or screwed back in unison, otherwise binding would occur. The operator would therefore be forced to shift from one screw to the other, turning each only a slight amount at one time. With the present arrangement each screw can be

adjusted continuously to its extreme position, the only requirement being that in moving the bar 14 down the screw 19 be operated first, and in moving the bar up, the screws 21 be operated first.

5   Mounted on arms 22 (Fig. 1) projecting downwardly from the frame 11 are the rollers 23, such rollers having concave rims as indicated in Fig. 2 with such rims in engagement with the upper surface of the guide bars 10. A similar roller 24 located between the rollers 23 engages the lower side of the guide bars 10, such roller being carried by the fork 25 projecting downwardly 10 from the frame 11. This roller has its axle 26 slidable at each end in a slot 27, the two sides of the fork 25 being similar in this respect. Beneath each end of the axle 26 of the roller is a spring 28, such spring in each 15 case bearing at its upper end against the axle and its other end bearing against a screw plug 29 whereby the tension of the spring may be adjusted. It will be seen that the foregoing arrangement provides for a 20 yielding engagement between the roller 24 and the lower side of the bar 10. All lost motion due to wear between the rollers and the bar 10 is thus taken up, and any play, which would tend to permit the frame 11 to 25 tilt sidewise, is eliminated. This arrangement is particularly advantageous in a machine of this character because of the large amount of gritty dust due to the grinding operation. This dust or dirt causes rapid 30 wear between sliding parts, and in the course of time an objectionable amount of play results. With the present arrangement this play is eliminated, and the blade 12 of the 35 adz is always held in exact parallelism with the bar 10. Another advantage of the construction resides in the fact that the rollers constitute antifriction means permitting the guides to work easily along the bar 10, and furthermore this arrangement involving the 40 use of the rollers or wheels with the concave rims permits the frame to rock transversely of the rod to bring the edge of the tool against the grinding disk or remove it therefrom.

45   When it is desired to grind a scythe the conical grinding wheel 4 is utilized. As indicated in Fig. 1, which shows a scythe 30 in cross section, all scythes are provided with a rib 31, thus giving a recess 32 adjacent the side of the scythe opposite the cutting edge. 50 In order to support and guide the scythe the roller 33 is provided, such roller having a flange 34 engaging the recess 32 at the side of the scythe. The engagement of this 55 flange 34 with the recess 32 prevents lateral movement of the scythe, there being sufficient play, however, to permit the scythe to be moved longitudinally across the axis of rotation of the grinding wheel 4. The bar 60 10 lying above the scythe assists in guiding

it and giving it the proper angle for grinding, and also serves to prevent the accidental disengagement of the grooved edge of the scythe from its supporting roller 33. The attachment permits of the accurate and convenient guiding of a scythe blade, without danger of injury to the blade or to the operator. The bar 10 not only serves to steady the blade and act as a guide therefor as the blade moves back and forth transversely of the bar and the wheel, but also prevents the blade from being turned at an improper angle, the relation of the roller and bar with respect to the grinding wheel 4 being such that when the edge of the blade engages the bar 10 it is at the proper angle with respect to the grinding wheel.

What I claim is:—

1. In combination in a grinding machine having a grinding wheel, a guide extending transversely of the axis of rotation of the wheel, a tool carrying frame mounted slidably on the guide, a movable clamping member guided at its ends on the frame, a screw threaded through the frame at the center of 85 the clamp and swiveled thereto so as to move the clamp in both directions, and other screws threaded through the frame on either side of the first screw and bearing against the clamp.

2. In combination in a grinding machine having a grinding wheel, a guide extending transversely of the axis of rotation of the wheel, a tool carrying frame mounted slidably on the guide and having a concave tool engaging surface whereby the tool to be ground is engaged on one side near its edges leaving the central portion out of engagement, and a clamp for engaging the tool on its other face.

3. In combination in a grinding machine having a grinding wheel, a guide extending transversely of the axis of rotation of the wheel, a tool carrying frame mounted on the guide, and antifriction means on the frame above and below the said guide and in engagement therewith, the said antifriction means being spring supported on one side of the said guide.

4. In combination in a grinding machine having a grinding wheel, a guide extending transversely of the axis of rotation of the wheel, a tool carrying frame mounted on the guide, a spring supported wheel carried by the frame and engaging the lower side of the guide, and a pair of wheels on the frame above the guide and engaging the guide on opposite sides of the first wheel.

5. In combination in a grinding machine having a grinding wheel, a round guide rod extending transversely of the axis of rotation of the wheel, a tool carrying frame mounted on the rod, and rollers with concave bearing rims carried by the frame and engaging the rod on the upper and lower

sides thereof for permitting the frame to move longitudinally of the rod and rock transversely thereof.

6. In combination in a grinding machine having a grinding wheel, a round guide rod extending transversely of the axis of rotation of the wheel, a tool carrying frame mounted on the rod, and rollers with concave bearing rims carried by the frame and

engaging the rod on the upper and lower sides thereof for permitting the frame to move longitudinally of the rod and rock transversely thereof, one of the said rollers being spring supported.

JOHN S. WINCRANTZ.
